United States Patent Office

Des. 186,408
Patented Oct. 20, 1959

186,408

CENTER POINT INDICATOR

Herbert T. Schramm, North Hollywood, Calif., assignor
to Lockheed Aircraft Corporation, Burbank, Calif.

Application July 1, 1957, Serial No. 46,788

Term of patent 14 years

(Cl. D54—13)

Fig. 1

Fig. 2

Fig. 3

Fig. 4

Fig. 5

Figure 1 is a perspective view of a center point indicator showing my new design;

Figure 2 is a side elevational view illustrating the split shank of the transfer point insert shown in Figure 1;

Figure 3 is a side elevational view of the transfer point insert taken at a right angle to view shown in Figure 2;

Figure 4 is a plan view of the transfer point insert shown in the above figures; and

Figure 5 is a bottom view of the transfer point insert shown in the above figures.

I claim:

The ornamental design for a center point indicator, substantially as shown.
